UNITED STATES PATENT OFFICE.

GEORGE H. CORLISS, OF PROVIDENCE, RHODE ISLAND.

IMPROVED STEAM-BOILER.

Specification forming part of Letters Patent No. 36,278, dated August 26, 1862.

To all whom it may concern:

Be it known that I, GEORGE H. CORLISS, of Providence, in the State of Rhode Island, have invented a new and useful Improvement in Steam-Boilers; and I do hereby declare that the following is a full and exact description thereof, reference being had to the accompanying drawings, in which—

Figure 1 represents a vertical section of my improved boiler; Fig. 2, a horizontal section or ground plan of the same.

At A is represented a circulating-reservoir for steam and water.

At B are represented cylindrical generators containing vertical tubes, within which the products of combustion are received from the furnace and passed into the chimney H.

At c c are shown connections for supplying water from the reservoir to the generators.

At d d are shown connections through which the heated water passes back into the reservoir.

At e e are shown passages for steam from the generators to the upper portion of the reservoir.

At f f is shown the water-line, which ought not to be below the apertures d d, nor so high as to interfere with the apertures e e.

At g g the fire-grates are shown; at i i the fire-doors.

A diaphragm is shown at k k, which forms the top of the furnace, through which the circulating-reservoir and the tubular generators pass.

By the construction of boilers in the manner now proposed the following important objects are combined: A rapid circulation of the water through the generators, whereby the heating-surfaces of the tubes are rendered highly effective. A boiler of this form can be conveniently handled and transported in sections. It combines great strength in proportion to the weight of materials used in its construction.

When the water in the boilers contains substances which are liable to be deposited, such deposition takes place in the circulating-reservoir A, in consequence of the much greater quiescence of the water in that reservoir than in the generators. These deposits fall upon a part of the apparatus which is not subject to the direct action of the fire, and they are made where they may be readily blown off.

In the accompanying drawings six of the generators are represented surrounding the circulating-reservoir; but this number may be increased or diminished without a departure from the principle of my invention.

When a single generator is desired, I sometimes place this concentrically within the circulating-reservoir, instead of arranging it as above described. In such cases I make the generator of smaller diameter than the reservoir and freely communicating with it both at the bottom and the top. The upward current which is caused by the products of combustion in ascending through the tubes descends along the intervening space between the generator and the surrounding reservoir, and, entering to the generator again at the bottom, keeps up a constant and rapid circulation upon the same principle as that already described.

Experience in the use of this form of boilers has shown that the spaces occupied by the steam and water in the generators should be at least four times that of the tubes.

What I claim as my invention, and desire to secure by Letters Patent, is—

The method of constructing steam-boilers by combining cylindrical circulating-reservoirs with cylindrical tubular generators, arranged and connected substantially as and for the purposes specified.

GEO. H. CORLISS.
